UNITED STATES PATENT OFFICE.

HENRY L. CARPENTER, OF MINNEAPOLIS, MINNESOTA.

FIRE-EXTINGUISHER.

No. 798,565.

Specification of Letters Patent.

Patented Aug. 29, 1905.

Application filed September 20, 1904. Serial No. 225,183.

To all whom it may concern:

Be it known that I, HENRY L. CARPENTER, of Minneapolis, Hennepin county, Minnesota, have invented new and useful Improvements 5 in Fire-Extinguishers, of which the following is a specification.

My invention relates to fire-extinguishers, and particularly to those of the hand type.

The object of the invention is to provide 10 means for insuring the successful discharge under pressure of the contents of a bottle filled with a fire-extinguishing liquid.

The invention consists generally in providing 15 a locking means in connection with the inner cork or plug of a bottle or receptacle containing a charged fire-extinguishing liquid to prevent said cork or plug from being accidentally blown out of the bottle when the pressure is released by the removal of the 20 outer cork.

In the accompanying drawings, forming 25 part of this specification, Figure 1 is a vertical section of a fire-extinguisher with my invention applied thereto. Fig. 2 is a section view of the top of the bottle, showing a modified means for connecting the tube to the inner cork or plug. Fig. 3 is a detail sectional view of the neck of the bottle, showing a modified form of locking device. Fig. 4 is 30 a detail of the locking device shown in Fig. 3. Fig. 5 is a modified form of locking device, and Figs. 6 and 7 illustrate further modifications.

In the drawings, 2 represents a bottle of 35 suitable size and shape adapted to be held in the hand and having a neck 3, provided with an annular groove or recess 4 for the purpose of weakening the bottle-neck at that point. The outer end of the neck is hermetically sealed by cork or plug 5, secured against 40 any accidental discharge from the bottle by means of wires 6. In place of the cork or plug a plastic material that will harden or set after being placed in the neck may be used.

The inner end of the cork 5 preferably terminates opposite the groove 4. Below the cork 5 and the groove 4 is a second or inner cork 7, having a hole 8 extending therethrough and provided with a tube 9, of any suitable 50 material, that extends into the bottle and has its open end near the bottom of the bottle.

The outer end of the bottle-neck is broken or knocked off by striking it against the corner of a table, chair, or other object preparatory to using the extinguisher, and to prevent the pressure of the charged liquid from

forcing the inner cork out of the bottle when the outer one is removed I provide a locking device interposed between said inner cork and the outer one and arranged to effectually lock 60 said inner cork against any possible dislodgment by the pressure of the gas in the bottle. This locking device may consist of a spider-like device 9', of metal or any other suitable material, having a hole 10, coinciding with 65 the hole in the cork, and arms 11, that are adapted to enter an annular recess 12 in the neck of the bottle and prevent any possible outward movement of the cork, the arms being preferably sprung into place, so that the 70 locking device will assume a concave form, as shown in Figs. 1 and 2. A tube 13 is preferably provided on the under side of the locking device, fitting snugly into the hole in the cork and abutting the upper end of the tube 9. 75

In Fig. 6 I have shown a modification in the form of the locking device which consists of a disk 14, of any suitable material, preferably thin sheet metal, capable of being used in the form shown in Figs. 1 and 2. If 80 preferred, some plastic material may be employed in place of the metallic disk, which, after becoming hardened, will securely lock the cork in the neck of the bottle.

In Fig. 5 I have shown still another modification in the locking device, which consists in providing a wire coil 15, having its ends inserted into the top of the cork and the coils following the circumference of the same and adapted to spring outwardly into the recess 85 90 and hold the cork in place.

In Figs. 3 and 4 still another modification is shown, which consists in providing a recess 16 a little lower down in the neck of the bottle and arranging a wire 17 over the top 95 of the cork having depending hooked ends 18, adapted to enter the recess and hold the cork in place.

Various modifications in the manner of securing the inner closing means in the neck 100 may be employed, and hence I do not wish to be confined to the devices shown and described herein.

I claim as my invention--

1. As a new article of manufacture, a receptacle having a neck provided with a weakened area, stoppers closing said neck above and below said area, a locking device engaging said neck and preventing the accidental discharge of said inner stopper, and a tube communicating with the interior of said receptacle and with the space between said stoppers. 105 110

2. As a new article of manufacture, a receptacle having a neck provided with a weakened area and having an annular groove or recess below said area, stoppers closing said neck upon each side of said area, a locking device extending across the inner stopper and entering said recess to prevent the accidental discharge of said inner stopper, and a tube communicating with said receptacle and with the space between said stoppers.
3. As a new article of manufacture, a bottle adapted to contain a liquid under pressure and provided with a neck having a weakened area and a recess below said area, stoppers closing said neck above and below said area, the inner stopper having a hole extending therethrough, a disk having a hole coinciding with the hole in said inner stopper, and edges adapted to enter said recess, and a tube fitting the hole in said inner stopper and extending into said bottle, substantially as described.
4. As a new article of manufacture, a bottle having a neck provided with a weakened area, stoppers closing said neck upon each side of said area, the inner stopper having a hole extending therethrough, a tube extending

into the bottle and communicating with said hole, and a locking device interposed between said inner and outer stopper and engaging the neck of the bottle and preventing the accidental discharge of said inner stopper, substantially as described.

5. As a new article of manufacture, a receptacle having a neck provided with a weakened area, means for closing said neck between said area and the receptacle, said closing means having an orifice extending therethrough, a tube communicating with said orifice and the interior of said receptacle, a locking device engaging said neck below said area and preventing the accidental discharge of said closing means, and means preventing the premature discharge of the contents of said receptacle through said tube and orifice, substantially as described.

In witness whereof I have hereunto set my hand, this 15th day of September, 1904, at Minneapolis, Minnesota.

HENRY L. CARPENTER.

In presence of—

A. C. PAUL,
RICHARD PAUL.
